DENTAL FLASK

James T. Hughes, Jr., Covington, Ky.

Application March 22, 1948, Serial No. 16,151

8 Claims. (Cl. 18—33)

1

This invention relates to molding flasks for forming sectional or built-up molds of formable material such as plaster of Paris. Specifically, the invention is directed to improvements in dental flasks for the casting of dental plates patterned from wax models.

An object of the present invention is to provide a flask structure for the casting of dental plates, or the like, from waste molds upon which external pressure may be exerted for the purpose of densification and compression.

Another object of the invention is to provide a dental flask of separable casing parts for the production of sectional molds.

A still further object of the invention is to provide a flask of separable parts so arranged that they may be opened or closed without displacing or disturbing the investment material or model embedded therein.

It is still a further object of the invention to provide a flask structure which permits the easy removal of the mold sections from the respective parts of the casing.

Still another object of the invention is to provide a flask, the parts of which can be quickly separated so that access can be had for building up the mold or for inspection and removal of the denture casting.

It is another object of the invention to provide means in a dental flask for aligning and locking the separable parts in their relative positions preparatory to subsequent casting operations.

Further objects and advantages are within the scope of this invention such as relate to the arrangement, operation and function of the related elements of the structure as described in the following specification and illustrated drawings, in which:

Figure 1 is a top plan view showing a preferred form of my dental flask.

Figure 2 is a side elevational view of the flask as shown in Figure 1.

Figure 3 is an end elevational view of this device.

Figure 4 is a sectional view taken on line 4—4 of Figure 1 showing the locking means and slide rods of the flask.

Figure 5 is an enlarged cross-sectional view taken on line 5—5 of Figure 1 showing in dot and dash lines the wax model or denture casting, as the case may be, and the respective parting surfaces of the sectional mold.

Figure 6 is a top plan view of the expander member for the main body part of the dental

2

flask showing in dot and dash lines the main body located thereon.

Figure 7 is a side elevational view of the member showing in dot and dash lines the main body of the flask located thereon.

Figure 8 is a top plan view of a modification of my invention partially broken away with a portion of the cope part removed, and in dot and dash lines a tool for the separation of the cope from the main body of the flask.

Figure 9 is an end elevational view of the modification shown in Figure 8 with a portion thereof broken away.

Figure 10 is a sectional view taken on line 15 10—10 of Figure 8 showing the self-retracting means of the main body of the flask.

Figure 11 is a top plan view of an additional modification of my dental flask, and

Figure 12 is another modification of the guide 20 and retracting means of the main body of the dental flask.

Referring in detail to the drawings, particularly to the structure shown in Figures 1 to 7 inclusive the invention is disclosed in the form of a dental 25 flask 15 of the three-flask part type, the casing 16 thereof, comprising a drag or lower part 17, a central main body or cheek part 18 and a cope or top part 19.

The drag 17 of the casing is a semi-elliptical 30 receptacle with side walls 20, having tool-slots 200 formed in the outer edge thereof for purposes to be later described, and to close the drag, the side walls are terminated by a flat bottom 21. Extending from the side are opposed integral 35 lugs 22 having vertically tapered bores 23 therethrough. This part of the flask is completed by a central hole 24 formed through the bottom 21 for the removable reception of the shank 25 of a button-headed punch 26.

The main body or cheek part 18 of the casing 40 is composed of two opposed side walls or equal sections 27 and 28 respectively, shaped substantially in conformity with the side walls 20 of the drag part. Integrally extended at right angles 45 from the adjacent ends 29 of each section are opposed flanges 30 and 31 having conforming holes 32 therethrough for the reception of guide rods 33.

Each of the guide rods are divided into two 50 portions, the stem 34 thereof being turned and terminated by an enlarged knurled head 35. Further, the stems of these portions are either internally or externally threaded, as the case may be, with the female threaded portion extended through the conforming pairs of holes 32 and adjustably retained therein by threaded engage-

ment to the male portion. Prior to mounting the rods 33 in the flanges, coiled springs 36 are placed about the stem portion 34, so that in assembly, a spring is positioned intermediate each head 35 and flange 30 or 31.

From the base of each flange 30 and 31 there is depended an integral half-dowel 37, which when the sections 27 and 28 are in their normal, spring urged retracted position, form steady-pins 38. The drag 17 and main body 18 of the casing are assembled or built-up and locked in a relatively lateral position, as shown in Figures 1 to 5 inclusive, by locating the steady-pins 38 of the cheek sections within the bores 23.

For knock-down purposes to be later described, tool-slots 39 are formed in the upper and lower annular outer edge of the cheeks 27 and 28 adjacent the flanges 30 and 31, also, tapered expander bores 40, of a common axial center are located centrally of the contiguous faces 41 of the flanges 30 and 31.

From the above description it is evident that the respective sections 27 and 28 of the cheek part are movable in parallel relation to one another through slide engagement of the rods 33 in the flanges 30 and 31. It is also apparent that the cheeks are held in a normal spring urged retracted position, but may be expanded or opened by a force sufficient to counteract the springs 36.

The cope 10 of the dental flask comprises a flat plate 42, and like the body 18, has a shape substantially in conformity with the side walls 20, with integral lugs 43, corresponding to those of the drag part 17, extending from opposed sides thereof. The lugs differ in structure from those of the drag part by provisions for maintaining the cope in an assembled lateral position with the main body 18. Yokes 44 therefore, perform a function as bores 23 of the drag, that is, retention of the sections 27 and 28 in a positive retracted position. A recess 45 is centered in the underside of each lug 43, thereby describing the yokes 44 as having a top 46 on a plane with the underside of the plate 42, and a pair of spaced depending legs 47.

A rectangular locating boss 48 depends integrally from the underside of the plate 42 intermediate the lugs 43, and is so positioned thereto, that it is longitudinally bisected by the common center line of the recesses 45.

For knock-down purposes, to be later described, tool-slots 49 are located in the outer annular edge of the underside of the plate 42 adjacent the lugs 43, where, they register with the slots 39 on assembly of the cope to the cheek part of my dental flask.

In assembly, the cope 19 is placed flush to the upper edge of the cheek 18, with the top portion of the flanges 30 and 31 inserted between the legs 47, thereby locking the sections 27 and 28 together in their normal retracted position. Thus assembled, the plane of the axial center line of the bores 40 bisect the boss 48.

For purposes of separating or expanding the cheeks 27 and 28 of the main body, there is provided an expander member 50, having the general appearance in side elevation of a rigid channel shaped body, comprising an apertured base 51 and opposed uprights 52 and 53. A hole is formed through each upright for the threaded reception of thumb screws 54. These holes are formed about a common center line, which when located vertically from the base 51, is of a distance equal to that from the top edge of the

main body 18 of the casing to the common center line of the expander bores 40. The ends of the screws 54 containing the first threads are conical having a tapered surface similar to bore 40 for insertion therein. A locating ridge 55, shaped identically as boss 48 of the cope part, extends from the exposed face of the base 51 intermediate the uprights 52 and 53. The position of the ridge to the base is such that it is longitudinally bisected by the vertical plane of the common center line of the screws 54.

To manufacture denture castings by means of my flask, a molder positions the punch 26 in the drag part 17 of the flask and forms the bottom mold section 56 by leveling-off wet plaster of Paris approximately even with the upper edge of the walls 20 of the drag. The wax model, reference numeral 57, is then embedded centrally within this mold section. All exposed plaster surfaces thereafter being painted with a material, such as water glass, to prevent union of subsequently added plaster sections thereto. The main body 18 is next assembled to the drag, locating the steady pins 38 in the bores 23. Additional wet plaster, to form the intermediate mold section 58, is now added to a depth level with the teeth crowns of the wax model 57, dot and dash parting line 59, where the exposed plaster surface is again painted. The top mold section 60 is now built-up by applying wet plaster at least to the upper edge of the main body 18. The casing 16 is now sealed and locked by assembling the cope 19 to the main body 18, locating the flanges 30 and 31 in the respective recesses 45.

After a hardening operation of the plaster the wax of the model 57 is liquefied and exhausted from the mold by removal of the drag part 17 and mold section 56 from the main body 18, thereby exposing the false teeth roots in the resulting mold cavity. A moldable denture material is inserted in this impression or cavity, made by the wax model, and the drag with the mold section 56 is laid back upon the cheek part for curing the denture material therein.

The curing operation includes the exertion of sufficient pressure upon the flask, by means of clamps or presses, to evacuate all air therefrom and insure a dental casting which has a true complementary shape as the cavity produced by the model 57.

The final operation in the production of dental castings by my flask, includes the removal of the drag and cope parts, the latter by means of tool 61 (Figure 8), from the main body 18 of the flask casing, thus leaving intact the intermediate mold section 58, with the dental plate therein, and the top mold section 60, with a locating groove impressed therein by the boss 48 of the cope part. Heretofore, the knocking out of finished casting from a plaster mold has been rather tedious and sometimes injurious to the finished product, however the incorporation of an expansible center or cheek part 18 in the structure of my invention in cooperation with the expander 50 has assured an easy knock-out operation with no possibility of injuring the casting by the application of hand tools. The remaining mold sections are removed from the cheek part 18 by assembly of this part to the expander 50, locating the ridge 55 in the impressed groove of the top mold section 60. In this position, Figures 6 and 7, the remaining mold sections 58 and 60 are released from the walls of the main body 18 by expanding the sections 27 and 28 through the medium of

wedging the tapered ends of the thumb screws 54 in the bores 40 of the flanges.

In the modified form of the invention shown in Figures 8 to 10 inclusive, there is depicted a simplified means for maintaining the sections 27 and 28 of the main body in their normal closed position and guided parallel relationship. Resilient clips 62, engaged in vertical slots 63 formed in the opposed faces of the respective flanges 30 and 31, are substituted for the springs 36 of my preferred structure, while guide pins 64 are positioned in the conforming holes 32 of the flanges in place of the rods 33. A perforation 65 has been made in the body of the clips 62 to assure exposure of the bores 40 to the expander 50.

The modification shown in Figure 11 has a main body part comprised of four cheek sections 66, 67, 68 and 69 respectively to adjacent ends which are terminated by a flange 70 and 71. These flanges are guided and resiliently maintained in a normal closed position by means previously described. This form of my invention also differs from the preferred structure in the necessity for appropriately locating additional lugs, same as lugs 22 and 43, to the drag and cope parts of the modified casing, and by the number of steady pins required for maintaining the respective parts of the flask in their relative lateral position.

The structure of Figure 12 depicts a modified means for retracting the sections of the cheek part, and consists in centering a countersunk bore 72 about the holes 32 of the flanges 31, threading the remaining holes 32 in the flanges 30, placing a coiled spring 73 in the bore 72, and finally inserting a threaded guide pin 74 therein to adapt the sections 27 and 28 for reciprocable movement in parallel relationship.

What is claimed is:

1. In a dental flask casing for forming sectional molds, the combination of a drag part, cheek part and cope part, said cheek part comprising a plurality of side by side sections the adjacent ends of which terminate in extended flanges having conforming holes, rods guided in the holes for reciprocable movement of said sections in parallel relationship, and means for locking said sections in closed position by assembling either the drag or cope parts thereto.

2. In a dental flask for forming sectional molds, the combination of a drag part, cheek part and cope part, said cheek part comprising a plurality of side by side sections each having adjacently disposed flanges, a lateral guide rod extending through said aligned holes to permit relative movement between said sections, spring means associated with adjacent end flanges for biasing the sections toward operative closed positions, and flange engaging stop means on the cope part and the drag part for locking the cheek part sections in closed position by assembling the cope and drag part to the said cheek part.

3. In a dental flask for forming sectional molds, the combination of a drag part, cheek part and cope part, said cheek part comprising a plurality of side by side sections each having adjacently disposed flanges, said flanges provided with contiguous faces having complementary half-bores centered therein, said half-bores being adapted to receive the cooperative wedge of a suitable expander tool, aligned holes formed in adjacently disposed flanges, a lateral guide rod extending through said aligned holes to provide relative movement between said section, spring means

associated with adjacent end flanges for biasing the sections toward operative closed positions, a boss depended from the underside of the cope part for forming a locating groove in the upper portion of the mold for engagement with a suitable ridge on said expander tool, and flange engaging stop means on the cope part and on the drag part for locking the cheek part sections in closed position by assembling the cope and drag part to the said cheek part.

4. In a dental flask, the combination of a cheek part comprising a plurality of sections the adjacent ends of which terminate in extended flanges having conforming holes, rods guided therein for reciprocable movement of said sections in parallel relationship, said flanges provided with contiguous faces having registerable half-bores centered therein, half-dowels depended from the base of said flanges which serve as steady-pins when said sections are in closed position, a drag part provided with extended lugs having perforations therethrough for lock insertion of the steady-pins, and a cope part comprising extended lugs.

5. In a device for making artificial dentures, the combination of a drag part, cheek part and cope part, said cheek comprising a plurality of sections the adjacent ends of which terminate in outstanding flanges having conforming holes, rods guided therein for reciprocable movement of said sections in parallel relationship, resilient means for maintaining the sections in closed position, said flanges provided with contiguous faces having registerable half-bores centered on the common plane thereof, said half-bores being adapted to receive the cooperative wedge of a suitable expander tool, and means for locking said sections in closed position by assembling either the drag or cope parts thereto.

6. In a dental flask for forming sectional molds, the combination of a drag part, cheek part and cope part, said cheek comprising a plurality of equal sections the adjacent ends of which terminate in extended flanges having conforming holes, rods guided therein for reciprocable movement of said sections in parallel relationship, resilient members mounted to said flanges for maintaining the sections in closed position, said flanges provided with contiguous faces having corresponding half-bores centered on the common plane thereof, half-dowels depended from the base of said flanges which serve as steady-pins when the sections are in closed position, said drag part comprising a plurality of extended lugs corresponding to the flanges and perforated for lock reception of the steady-pins, said cope part comprising a plurality of extended lugs corresponding to the flanges and recessed to form a yoke for lock reception of said flanges, and a boss depended from the underside of the cope part for forming a locating groove in the upper portion of the mold.

7. In a dental flask of the class described, a cheek part comprising a plurality of sections, flanges extended from the adjacent ends thereof having conforming holes therethrough, rod-like members guided therein for reciprocable movement of said sections in parallel relationship, each of said members comprising a stem terminated by opposed heads, coiled springs mounted to said stem intermediate the head and flange for maintaining the sections in closed position.

8. In a dental flask of the class described, a cheek part comprising a plurality of sections, flanges extended from the adjacent ends thereof having conforming holes therethrough, rod-like

members guided therein for reciprocable movement of said sections in parallel relationship, said flanges provided with opposed faces having vertical slots therein, a resilient U-shaped clip mounted in said slots for maintaining the sections in closed position.
